UNITED STATES PATENT OFFICE.

MAX CHRISTIAN ZANGE, OF CINCINNATI, OHIO.

HAND VISE.

Application filed October 16, 1922. Serial No. 594,708.

To all whom it may concern:

Be it known that I, MAX CHRISTIAN ZANGE, a citizen of the United States of America, and a resident of Cincinnati, in the county of Hamilton and State of Ohio, have invented a certain new and useful Improvement in Hand Vises, of which the following is a specification.

This invention relates to hand-vises or hand-chucks used by mechanics and others in conveniently holding and handling small pieces or narrow lengths of material in connection with bench-vise, bench-anvil and other similar hand-manipulated work, and the peculiar structure of the invention, including its objects and advantages, claimed by me herein, are minutely and fully described in connection with the accompanying sheet of drawings, in which—

20 Figure 1 is a front elevation of the improved hand-implement embodying my invention and showing in clamped-position therein an elongated round-section piece or strip of work-material ready for manipulation in connection with a bench-vise, anvil, block, or other suitable base or resting-surface, and thus facilitating the use of a shaping-hammer, or of a dressing or finishing file or other tool customarily used in machinist's or other mechanic's work; Fig. 2, an upper end view of the said implement and its clamped work-piece, the latter being shown in cross-section, for clearness; Fig. 3, a left-side elevation of the implement seen in Fig. 1; Fig. 4, an elevation, similar to Fig. 1, but made partly in section, the sectional parts being of the jamb or thumb nut and one end of the spanner draw-bolt and its side-bars located at the upper end of the pair of jaw carrier-members, and, also, of the jaw-carrier spreader and jaw-closure device located at the lower part of the implement, and including one of the upright wing or side-plate extensions on the spreader supporting-sleeve for adjustably-coupling the lower ends of the said jaw carrier-members; Fig. 5, a transverse section taken on the horizontal dotted-line 4, 4, of Fig. 4, to more clearly show the spanner draw-bolt at the upper part of the assembled jaw carrier-members; and Fig. 6, a vertical, central or axial section of the implement, but with the lower jaw-closure or wedge device and its manipulating-head in elevation, and, also, with the strip of work-material omitted.

7 and 8 together indicate a pair of corresponding main jaw carrier-members, the carrier-member 7 being the movable one of the pair in correlation to the other carrier-member 8 in so far as the opening of the upper grip or clamp jaws proper 9 and 10 are concerned, for holding-engagement with the work, the parts 11 and 12 indicating, respectively, the shanks or body-portions of the said jaw carrier-members 7 and 8, and composed of flat bars that have the broadened or transversely-extended grip or clamp jaws proper 9 and 10 at their respective upper ends, circular enlarged openings or holes 13 near their lower ends, and transverse flatly recessed or countersunk portions 14, the latter produced on both sides of the shanks, clear across the face or width thereof, just below the inwardly-curved end-walls of the said grip or clamp jaws 9 and 10. The inner faces of the said grip or clamp jaws 9 and 10 are both checkered or criss-crossed for the better holding-engagement with the work placed between them.

15 and 16 together indicate a corresponding pair of horizontal partially flat bars or plates extending integrally from a screw-threaded circular end-portion or bolt-eye 17 and spanning the countersunk portions 14 of the two jaw carrier-members 7 and 8, and pivotally-connected to the carrier-member 8 by means of the rivet 18. The spanner or forked bars or plates 15 and 16 that extend from the threaded bolt-end 17 are flat ones about half their lengths, but are round the balance of their lengths for the provision of a screw-thread 19 of sufficient length to accommodate the jamb or thumb nut 20 a suitable distance along it for the desired closing of the grip-jaws proper 9 and 10 on the very thinnest work as well as for any variegated work that is expected to be placed or inserted in the implement for file and other service.

It will be readily seen, in a number of views of the drawing, that the flat countersunk-portions 14 are somewhat wider than the width of the spaced spanner-bars 15 and 16 of the split or forked draw-bolt 17, and, more especially, the countersink 14 on the two flat faces of the movable jaw carrier-member 7, so that due allowance is thereby made for the swinging-movement of the said movable carrier-member 7 to and from closed clamping engagement with the work between the said grip-jaws proper 9 and 10.

It will be seen, too, and very particularly so in the successful carrying out of the important object and quite essential feature of my invention herein, which is that of a clear 5 and absolutely unobstructed broad passageway throughout the longitudinal center or axis and beyond both ends of the entire implement herein, that the said draw-bolt spanner bars or plates 15 and 16 are located at both 10 sides of the central passageway, at right-angles to the inner edges of both of the jaw-shanks 11 and 12. Besides, the circular openings or holes 13 in the lower ends of the said jaw-shanks are somewhat enlarged 15 beyond that of the diameter or sectional area of the rivets 21 that I will now refer to more directly in connection with the internally-threaded ring or sleeve 22 that has a pair of duly corresponding upright wings or side- 20 plate extensions 23 and 24 which each have holes pierced therein about midheight for accommodating the said rivets 21. The rivets 21 extend through the wings 23 and 24 and through the said enlarged holes 13 in the 25 jaw-shanks, but the wings are not drawn so tightly together as to prevent the jaw-shanks having a free sliding-movement between them to compensate for the adjustment of the movable jaw carrier-member 7 30 in relation to the companion jaw carrier-member 8 for the proper closing of the grip-jaws proper 9 and 10 on the work, no matter how thick or how thin the latter might be, consistent with the range or capacity of 35 the tool or implement herein, and to provide an adjustment of the jaws that is parallel to that of the longitudinal surface of the work being held.

A circular or round ended vertical wedge 40 25, forming a spreader or expander, is provided in the said internally-threaded sleeve 22, its outer surface being screw-threaded for engagement with said sleeve 22, and its upper end is beveled or tapered at 26 for 45 spreading-engagement with the tapered or beveled lower ends 27 of the said jaw-shanks, as best shown in Fig. 4, for forced closing of the grip-jaws proper 9 and 10 on the work.

An enlarged knurled lower end or head 28 50 is provided on the said spreader or wedge 25 for use in forcibly turning the latter into spreading-engagement with the said beveled lower ends of the jaw-shanks and, also, for readily releasing the jaw-members from the 55 work when service on the latter has been completed, or it is otherwise desired to change the position of the work in the implement. A series of holes or orifices 29 is provided in the said knurled lower head or 60 handle of the wedge 25 for the special purpose of "extra" tightening of the grip-jaw members on the work when required, and which quite often occurs on short pieces, or 65 on undue thick or thin ones, or on those having peculiar or irregular surfaces.

In operating the implement, the work or piece of material A, that may be an elongated strip or piece of round cross-section metal, as shown, or it may be a short one of other cross-section, or it may be a strip of 70 wire, as the case may be, is inserted between the jaw-members 9 and 10 while the latter are in open condition, of course, with the opposite ends of the work extended beyond the oposite ends of the implement without 75 any hindrance or obstruction whatever and as its length, that may be varied, may be best served or accommodated; then the grip-jaw members proper 9 and 10 are both brought into easy close touching-contact with 80 the said strip of work by simply turning the jamb or thumb nut 20 forward along the threaded-portion of the outer uniting-end or draw-bolt 17 of the spanner-bars 15 and 16 until the inner face of said jamb or 85 thumb nut just touches or contacts easily with the outer face of the upright movable jaw-shank 11, whereby the latter is moved forward and just lightly causes the grip-jaw proper 9 to engage the work and force 90 it just as lightly into contacting-engagement with the companion grip-jaw proper 10; and then the wedge or spreader member 25 is turned upward or forward within the 95 sleeve 22, using the lower head or handle 28, in forcibly doing so, until the lower beveled or tapered ends of the jaw-shanks 11 and 12 are spread outwardly so as to simultaneously close the said grip-jaws proper 9 and 10 100 into final tight-contact with the work, ready for active service on the latter, as desired. The pivotal-movement of the movable grip-jaw member 7, as well as what pivotal-movement there is in the lower end of the companion jaw-shank 12, is an important one at 105 this juncture, for the reason that it provides for the unincumbered "extra" tightening or clamping of the work A between the grip-jaws proper 9 and 10, and forms a decidedly firm hold or grip on the said work to prevent its slipping or shifting in any or either direction while mounted in the implement 110 herein.

The jaw-shanks and the balance of the implement below the jamb or thumb nut form 115 a handy, as well as comfortable, handgrasp in the use thereof wherever that may be.

I claim:—

In a work-holding hand-vise or hand-chuck implement, the combination of a pair 120 of jaw carrier-members having enlarged openings in the lower tapered ends of their shanks or body-portions, transversely-elongated grip-jaws provided at the upper ends of the said jaw carrier-members, an open split-ended draw-bolt adapted to span the upper ends of the said carrier-members beneath said grip-jaws and to be pivotally-connected at its outer split end to the adjacent jaw carrier-member, a thumb-nut 125 130

- mounted on the threaded closed end of said draw-bolt and adapted to initially close the grip-jaws on the work that is extended downwardly through the implement in an unobstructed straight axial manner or passage from end to end thereof and beyond both ends as may be required, an internally-threaded sleeve having a pair of spaced upright side-wings and adjustably-connected to the lower ends of the said jaw-carrier shanks by means of pins or the like that extend through and engage the said enlarged openings in the jaw-carrier shanks, and an externally-threaded spreader having a wedge-shape upper end for expanding engagement with the said lower tapered ends of the jaw-carrier shanks and, also, for engagement with the said internally-threaded sleeve, and, also, having a manipulating-head at the outer end of said spreader or expander for use in turning the latter in opposite directions for the final tight gripping of the jaws on the work and permitting their release, respectively, substantially as herein shown and described.

MAX CHRISTIAN ZANGE.
